GERSTEIN & BORUN LLP

(57) CLAIM

The ornamental design for a finger-mounted gripping tool, as shown and described.

DESCRIPTION

2. Finger-mounted gripping tool

2.1 : Top, front perspective

2.2 : Front

2.3 : Right

2.4 : Back

2.5 : Left

2.6 : Bottom

2.7 : Top

The broken lines in the drawings depict portions of the finger-mounted gripping tool that form no part of the claimed design.

1 Claim, 7 Drawing Sheets
